UNITED STATES PATENT OFFICE.

ROBERT J. THOMAS, OF HOUULTON, MAINE, ASSIGNOR OF ONE-HALF TO
ALEXANDER R. RICE, OF BOSTON, MASSACHUSETTS.

TUBULAR LANTERN.

SPECIFICATION forming part of Letters Patent No. 309,896, dated December 30, 1884.

Application filed April 25, 1884. (No model.)

To all whom it may concern:

Be it known that I, ROBERT J. THOMAS, of Houlton, in the county of Aroostook and State of Maine, have invented a new and useful Improvement in Tubular Lanterns; and I do hereby declare that the following is a full and exact description of the same, reference being had to the accompanying drawings, and to the letters of reference marked thereon.

10 My invention relates to that class of lanterns in which a concave disk is secured to the central tube of a continuous draft-tube, which latter forms the supporting-frame of the lantern; and the novelty consists in the 15 construction, arrangement, and adaptation of parts, as will be more fully hereinafter set forth, and specifically pointed out in the claims.

The invention is designed as an improvement upon Patent No. 244,944, of 1881, in 20 which devices for raising, supporting, lowering, and securing the globe of a lantern were arranged to conveniently and speedily allow the filling, trimming, lighting, or extinguishing of the lamp. In such construction, however, not only were the tubes which comprise 25 the supporting-frame left standing in a vertical position, but, owing to such vertical position, the globe and its adjuncts had to be supported by a spring-catch. This spring- 30 catch was necessarily provided with two locking-shoulders—one to hold the globe locked and the other to hold it elevated.

My invention contemplates hinging the draft-tube, to allow a portion of it to be lowered into a horizontal position entirely out of 35 the way of the operator, and by reason of such construction I avoid the necessity for locking the globe in an elevated position, as well as the necessity for elevating such globe 40 to any distance beyond its point of contact with the cone of the burner.

The invention is fully illustrated in the accompanying drawings, in which Figure 1 is an elevation of a lantern embodying my invention, and showing the globe and supporting-frame locked in position for use; and Fig. 2 is a perspective view of the lantern, showing the globe and supporting-frame lowered.

Referring to the drawings, A designates the oil-reservoir, having the usual burner and cone, 50 a; B, the globe, and C the movable frame supporting such globe, and having the concave disk c, which is provided with a spring, c', and the perforated plate d.

F designates the horizontal portion of the 55 draft-tube, which is rigid with the oil-reservoir; and F', the remaining portion of said tube. These parts are of ordinary construction, except that the part F' of the draft-tube is loosely jointed with the part F thereof by 60 one of the parts telescoping with the other, one part being provided with locking-pins, as g, and the other with corresponding recesses, as g'. The material of the frame F' allows its lower arms to be spread sufficiently 65 to disengage these locking devices g g', and the arms C' of the frame C serve to hold the said locking devices together when the frame F' is in a vertical position.

It will be observed that it is only necessary 70 that the globe and its frame should be held into proper relation with the burner for use, and that it is only necessary to elevate the same sufficiently to allow the plate d to clear the cone of the burner in order to lower the 75 entire frame and globe out of the way.

I have shown a spring-catch, i, for holding the globe down upon its seat; but this catch is not necessary for holding the globe at any point of elevation.

I attach importance to the construction whereby the folding portion of the frame is connected with the rigid portion thereof by a duplex telescopic joint. This allows the parts to be readily put together in the first instance, 85 and as readily separated as occasion may require. It also forms an enlarged bearing and durable joint.

Having fully described my invention, what I claim as new, and desire to secure by Letters 90 Patent, is—

1. In a lantern, substantially as described, a tubular frame made in two parts, as F F', removably joined to each other by a telescopic joint upon either side of the burner, the 95 part F being rigid with the reservoir, and

the part F' being adapted to turn freely upon said rigid part to form a hinge, as set forth.

2. In combination with the draft-tube, consisting of the parts F and F', loosely connected together by a telescoping joint, a movable glebe-frame having locking-arms C', and engaging locking means, as g g', substantially as and for the purpose set forth.

This specification signed and witnessed this 7th day of April, 1884.

ROBERT J. THOMAS.
